UNITED STATES PATENT OFFICE.

FRANK J. LEONARD, OF OLIVIA, MINNESOTA.

COVER-OPENER.

1,142,446.

Specification of Letters Patent.

Patented June 8, 1915.

Application filed July 10, 1914. Serial No. 850,139.

To all whom it may concern:

Be it known that I, FRANK J. LEONARD, citizen of the United States, residing at Olivia, in the county of Renville and State 5 of Minnesota, have invented certain new and useful Improvements in Cover-Openers; and I do hereby declare the following to be a full, clear, and exact description of the invention, such as will enable others skilled 10 in the art to which it appertains to make and use the same.

My invention has for its object to provide an improved cover opener for boxes, cans, and the like, having telescoped covers, 15 wherein the opener is permanently secured to the body of the receptacle in a position to engage the cover, under a rotary movement of the opener, and thereby impart the initial opening movement to said cover. 20 To the above end, the invention consists of the novel devices and arrangement of parts hereinafter described and defined in the claim.

In the accompanying drawings, which 25 illustrate the invention, like characters indicate like parts throughout the several views.

Referring to the drawings, Figure 1 is a view in side elevation, showing a box, having applied thereto the improved cover 30 opener, some parts being broken away, and some of the exposed parts being shown in section; Fig. 2 is a plan view of the same; Fig. 3 is a view corresponding to Fig. 1, with the exception that the cover is partly 35 opened by the improved opener; Fig. 4 is a detail view in plan, on an enlarged scale, of the improved opener and a portion of the box; and Fig. 5 is a transverse vertical section, taken on the line $x^5 x^6$ of Fig. 3, on an 40 enlarged scale.

The numeral 1 indicates the body of a metallic box, having a cover 2 telescoped thereon. The closing movement of the cover 2 onto the body 1 is limited by an outwardly 45 pressed annular stop bead 3, formed in the side wall of the body 1, slightly above the intermediate portion thereof.

The box illustrated in the drawings has been shown simply to give one form of receptacle to which the invention may be 50 applied.

The improved cover opener is, as shown,

in the form of a turn button 4, pivoted to the side of the box body 1 by a rivet 5, for complete rotary movement. At each end of the turn button 4 is formed an outwardly and inwardly beveled shoulder 6 and a finger piece 7. The bottom of the turn button 4 is longitudinally formed concave and that portion of the box body 1, over which 55 said turn button rotates, is outwardly pressed to form a convex surface which closely fits within the turn button at all 60 positions thereof.

When the cover 2 is closed, as shown in 65 Fig. 1, the turn button 4 is in a horizontal position parallel with the lower edge of said cover and alined with the bead 3. To impart the initial lifting movement to the 70 cover 2, the turn button 4 is rotated by the finger pieces 7, which brings either of its shoulders 6, depending on which way the 75 same is rotated, into engagement with the lower edge of said cover. The beveled shoulders 6 cause the turn button 4 to enter 80 between the box body 1 and cover 2 and thereby prevent the cover from slipping off from the turn button during the rotation thereof. These shoulders also tend to draw the adjacent portion of the cover flange out 85 of engagement with the body of the box and thereby assist in the opening movement of the cover. The concavo-convex engagement of the turn button 4 and box body 1 also prevent the turn button 4 from slipping past the lower edge of the cover 2, 90 without engaging the same and positively insure the engagement of the shoulders 6 with the cover.

What I claim is:

The combination with a receptacle having a cover telescoped thereon, of a cover opener comprising a turn button pivotally secured to the receptacle for engagement with the edge of the cover, said turn button 95 having a concave surface fitting a spherical surface on the receptacle.

In testimony whereof I affix my signature in presence of two witnesses.

FRANK J. LEONARD.

Witnesses:

A. W. NELSON,
BEN LEONARD.
